SHANK POURING POT

Harold Wallis, Oakmont, Pa., assignor to American Steel Foundries, Chicago, Ill., a corporation of New Jersey

Application July 22, 1947, Serial No. 762,551

1 Claim. (Cl. 22—83)

1

My invention relates to improvements in the art of manufacturing metal founding ladles or shank pouring pots.

Heretofore in foundry practice it has been customary to utilize what are commonly known as "round" pots, the designation characterizing the pot as being cylindrical, conical or spherical in shape.

In preparing such pots for founding metals, such as steel, it is common practice to line the pot with refractory material such as ganister lining or fire clay, this lining process being generally performed by the user who hand-rams the lining into the pot while the lining is in wet and plastic state, the operation usually taking about an hour to complete.

The lining is then hardened and dried by heating the pot for about three or four hours, it being understood that if the pot were filled with hot metal while the lining was still wet, the heat would glaze the exposed surface of the lining and thereby trap the moisture between the metal wall of the pot and said exposed surface of the lining. Furthermore, the heat of the molten metal would change the moisture into steam with sufficient pressure to cause disruption of the lining and distortion or rupture of the metal wall of the pot. Another reason for drying the lining is to prevent metallurgical difficulties with the molten metal.

Obviously, this process is not only time-consuming but is also costly and necessitates the use of numerous pots if the casting operation is continuous.

Another disadvantage to the use of "round" pots is that in pouring metal from such a pot into molds during the casting operation, the metal issuing from the pot runs in a flat stream which chills the metal and results in misruns.

After the pot has been in use for some time, the lining burns out, requiring removal of the old lining and relining the pot. The removal of the old lining is often complicated by the presence of skull metal which forms a hard crust on the exposed surface of the old lining and prevents it from falling out of the pot upon hammering the metal shell or walls of the pot, as a consequence of which the skull metal and old lining must be dug out, a long and tedious process. In removing the old lining, the shell is subjected to much battering, thus materially reducing the life of the shell.

The primary object of this invention is to provide a novel method and means for lining a foundry pot with slabs of predried preformed refractory material to reduce the time required for lin-

2

ing the pot, for drying it, and for preheating it preparatory to its use.

Another object of the invention is to devise a square pot preferably in the form of an inverted truncated pyramid wherein the sides of the pot are arranged to define a plurality of sharp corners forming alternately usable pouring lips for directing molten metal from the pot into the molds in a thick stream, whereby rapid chilling of the metal during such pouring operation is prevented.

A further object of the invention is to devise a pot of such form that it may be easily lined interiorly thereof with preformed slabs of dry refractory material and wherein the slabs lining the sides of the pot may be arranged in overlapping relation and interlocked with each other to keep each other in place against the sides of the pot.

One modification of the invention comprehends the provision of a square split pot wherein the shell is made in two separable pieces parted at diagonally opposite corners, the pieces being secured when in use by bolts and keys, this improvement being valuable in reducing the time required to remove an old lining and in preventing abuse of the shell with consequent lengthening of its life.

In the one modification of the invention, a preformed brick sleeve or spout is provided, the sleeve being fixed to one of the corners of the pot by cementing it in place to the brick lining of the pot.

A still further object of the invention is to devise a shank pouring pot which is of simple, convenient form, is inexpensive to manufacture, and is particularly well suited for the purpose intended.

These and other objects of the invention will be apparent from the specification and the drawings, wherein:

40 Figure 1 is a top plan view illustrating one form of pot constructed in accordance with my invention.

Figure 2 is a side elevation of the structure shown in Figure 1.

45 Figure 3 is a sectional view of the same, taken in the plane substantially as indicated by line 3—3 of Figure 1.

Figure 4 is a plan view of a lid for the pot shown in Figures 1 to 3.

50 Figure 5 is a side elevation of the lid, the view being taken from the right of the structure shown in Figure 4.

Figure 6 is a view illustrating the application of the lid to the pot, the pot being fragmentarily shown in phantom lines.

Figure 7 is a side elevation of one of the pre-formed bricks used in lining the sides of the pot.

Figure 8 is a plan view of another type of pot made in accordance with the invention; and

Figure 9 is a sectional view of the structure shown in Figure 8, the view being taken in the plane substantially as indicated by line 9-9 of Figure 8.

Describing the invention in detail and referring first to the modification illustrated in Figures 1 to 7, the pot or ladle 2 is generally in the form of an inverted truncated pyramid and comprises an outer metallic shell made up of two substantially identical V-shaped abutting separable halves or sections 4, 4 parted at diagonally opposite corners of the pot as at 6, 6.

Each section comprises a pair of angularly related side webs 8, 8 sloping inwardly, downwardly, and joined at one edge to each other. The webs are formed at their lower edges with inturned flanges 10, 10 and are provided at the edges opposite those which are joined with outwardly extending flanges 12, 12.

The two halves of the outer shell are detachably connected to each other by bolts 14 and keys 16, the bolts being square and projecting through complementary aligned openings 18, 18 in the abutting mating flanges 12, 12.

A square metallic plate 20 is removably fitted into the shell and is seated against the inner surfaces of the flanges 10, 10. The plate 20 forms the bottom or base of the pot and the webs 8, 8 form the sides of the pot and it will be observed that the webs are so related that they form four sharp corners of the pyramidal pot.

Each section 4 is provided with a trunnion 22 formed integrally with the side webs 8, 8 thereof at the apex of the juncture of said side webs intermediate the top and bottom edges thereof, said trunnions in the assembled position of said sections extending in opposite directions from the diagonally opposite corners of the pot and affording the usual connection for means (not shown) for suspending and transporting the pot from a tram rail, as will be readily understood by those skilled in the art. The trunnions, although shown as being integral with the side webs, may be connected to the side webs in any convenient manner, as will be readily understood by those skilled in the art.

Each trunnion has a socket 24 adapted for connection with a bailing lever (not shown) of usual construction for tilting the pot on said trunnions.

The pot thus far described is lined on the interior surfaces thereof with a relatively thin layer of a plastic refractory material 26, such as fire clay or cement, the refractory material sealing all the cracks in the outer shell of the pot and filling in all the irregularities in the shell. The refractory material 26 is molded so that it presents a continuous relatively smooth exposed surface interiorly of the pot. The interior of the pot is additionally lined with preformed predried flat slabs of refractory brick lining, such as tile bricks. The brick lining, as may be seen in the drawings, includes a square brick bottom 30 and a plurality of identical trapezoidal-shaped side bricks 28, 28, one of which is shown in Figure 7, said side bricks 28, 28 lining the sides of the pot and said bottom brick being seated on the refractory material 26 on the bottom plate 20 of the pot. The bottom brick supports the side bricks 28, 28 which are seated at their bottom edges on the bottom brick adjacent the marginal edges 75

thereof. The side bricks 28, 28 protrude above the side webs 8, 8 of the shell and the space between the upper edges of the bricks 28, 28 and the top edges of the side webs 8, 8 is filled in with the refractory material 26 as at 32, thus affording protection for the sides of the pot when molten metal is being poured therefrom.

The slabs 28, 28 are embedded in the material 26 lining the side webs 8, 8 and abut each other at their ends and are interlocked with each other in the pot in such manner as to keep each other from falling out of place, that is, each slab 28 bears at one end against the inner or exposed side of an adjacent slab as at 34 and at the other end overlaps the end of the other adjacent slab as at 36 (Figure 1). After the brick lining has been fitted into place, all corners where the bricks meet are sealed with the material 26 to prevent seepage of metal between said bricks.

At one corner of the pot where the two sections of the outer shell are joined is positioned a spout or cylindrical sleeve 38 which is also made of refractory material. The spout extends from the top to the bottom of the pot and is cut away at the lower end thereof as at 40, defining a passage communicating with the interior of the pot and a passage 42 through the spout, the spout serving to drain the metal off the bottom of the pot, as will be readily understood by those skilled in the art.

The spout is held in place by refractory plastic material 44, such as fire clay, molded around a portion of the spout and bonded to the adjacent side brick slabs 28, 28, said spout being additionally held in place by bonding the bottom of the spout to the bottom brick slab by a plastic refractory material as at 46 (Figure 3).

To prepare the pot thus far described for founding molten metals, the pot is heated to dry the plastic refractory material and to bring the brick slabs up to required temperature. In this connection the side webs 8 may be perforated at spaced points as at 48, 48 (Figure 2) to facilitate the drying of the plastic refractory material 26, and it will be appreciated that in drying, the plastic material forms a firm bond between the brick slabs and the outer shell of the pot. The drying process takes only a relatively short time to complete since only the thin layer of material 26 needs be dried, it being understood that the brick slabs are dry at time of assembly.

The pot is provided with a substantially square lid 50, the lid being reinforced by a plurality of spaced rods 52, 52 welded to a depending skirt 54 formed around the marginal edges of said lid, the skirt being adapted to seat on the top edge of the pot. One of the corners of the lid 50 is cut off as at 56 to afford clearance for the spout.

At one corner of the lid adjacent the cut-off portion thereof is secured, as by welding, a depending rod 60 which fits into a sleeve 64 disposed at one corner of one of the sections and welded thereto as at 68, said rod 60 in cooperation with said sleeve 64 serving to hold the lid on the pot. The sleeve 64 is split as at 66 at its upper end on its inner side to afford clearance for the skirt 54 and permit the same to seat on the top edge of the pot.

On the skirt 54 at a side opposite the cut-off portion of the web 52 is welded a depending rod 70, the rod 70 being adapted to engage the adjacent side web 8 of the outer shell to prevent the lid from shifting when the pot is tilted in pouring.

The disassembly of the pot 2 for relining is rela-

tively simple. The keys and bolts connecting the two sections of the outer shell are removed. The two sections of the shell are pulled apart, thus dropping the bottom plate. Any refractory material adhering to the sides of the two sections is loosened by tapping the side webs 8, 8. After removal of the old lining, to assemble this pot the two sections are secured to each other. The bottom plate is seated on the flanges 10, 10. The interior of the pot is lined with a coating of the plastic refractory material 26, which is manually applied while in a plastic condition and is formed roughly in the shape shown best in Figure 3. The bottom brick slab is seated at the bottom of the pot, care being taken to center the bottom slab so that there is a filling of the material 26 between the marginal edges of the bottom slab and the interior surfaces of the side webs 8, 8. Each slab 28 is separately inserted into the pot and arranged in the positions shown. The space between the top edge of the pot and the upper edge of the slabs 28 is filled in with the refractory material 26 and all spaces between the bricks are sealed with the material 26. The tile spout is then cemented to one of the before mentioned corners of the pot, and the pot is heated to dry the material 26 and heat the brick slabs. This completes the preparation of the pot and places it in condition for immediate use.

Referring now to Figures 8 and 9 illustrating another modification of the invention, the shank pouring pot or ladle 100 is in general of the same pyramidal form as that shown in the first-described modification, the pot 100, however, comprising an integral one-piece outer metallic shell 102 having side webs 104, 106, 108 and 110 and a bottom plate 112 (Figure 9) secured at its marginal edges to the lower edges of the side webs as by welding. The side webs it will be noted, slope inwardly, downwardly, and adjacent side webs are arranged at right angles to each other and are connected to each other at their side edges and define four sharp corners.

As in the previous modification, the interior of the shell is lined with a relatively thin coat of cohesive plastic refractory material 114 (Figure 9), such as fire clay, and is additionally lined interiorly thereof with side slabs 116, 116 and a bottom slab 118 of preformed pressed, pre-dried refractory brick. The slab 118 is of square shape and is seated in the material lining the bottom plate 112, the slab 118 being centered in the shell so that the marginal edges thereof are spaced from the inner surfaces on the side webs, the space between the edges of the slab 118 and the inner surfaces of the side webs being filled in with the refractory material 114. The slabs 116, 116 are of the same form as the side slabs 28, 28 described in the previous modification and are seated at their lower edges on the interior surface of the bottom slab 118 as at 120, 120 (Figure 9) adjacent the marginal edges thereof and on their exterior sides seat against the material 114 lining the sides of the pot. The slabs 116, 116 are arranged in interlocking relation to keep each other from falling out of place, that is, each slab 116 bears at one end against an interior surface of an adjacent slab 116 and at its other end overlaps the edge of the other adjacent slab 116.

The slabs 116 protrude above the side webs of the shell, the top edges of which are bent to form a bead 122 on which is molded as at 124, 124 a portion of the refractory material 114 extending

5 to the top edges of the slabs 116, 116 and affording protection for the sides of the pot when pouring molten metal therefrom. To prepare the pot 100 thus far described for pouring molten metal, the pot is heated to dry the refractory material 114 and to bring the slabs up to required temperature. To facilitate drying the material 114 and prevent entrapment of vapors between the outer shell and the brick slabs, the side webs are perforated as at 126, 126.

10 At opposite sides of the pot on the side webs 106 and 110 thereof are provided brackets 130, 130 secured to said webs as by welding and affording a support for the pot on a suitable hand shank (not shown) for carrying and bailing the pot, as will be understood by those skilled in the art.

15 The pot thus formed presents a plurality of sharp corners, any of which may be used in top 20 pouring of molten metal.

25 To remove the lining, the pot is tipped upside down and is tapped by a mallet or hammer on the sides and bottom, thus loosening the lining from the shell and permitting it to drop out.

20 The assembly of the lining in this pot is identical with that described in connection with the first modification.

30 It is to be understood that I do not wish to be limited by the exact embodiments of the device shown which are merely by way of illustration and not limitation as various and other forms of the device will, of course, be apparent to those skilled in the art without departing from the spirit of the invention or the scope of the 35 claim.

I claim:

40 A foundry pot comprising two mating side sections and a flat bottom section arranged to form a four-sided frusto-pyramidal shell, each side section comprising a pair of panels integrally united at one of their vertical edges to each other to form two adjacent sides and an included corner of the pot, each panel having an outturned flange at its other vertical edge, 45 the flanges of adjacent panels on the respective side sections abutting against each other, bolts extending through complementary openings in abutting flanges, wedge keys cooperating with said bolts to lock said side sections together, each 50 panel having an inturned bottom projection at its lower edge, said bottom section comprising a quadrilateral plate having a complementary fit within the bottom of said pot and seated on said projections, said side sections forming two diagonally opposite corners of the pot at said abutment of said flanges, trunnions extending from the other diagonally opposite corners of the pot, each trunnion being joined to the adjacent side section at the juncture of the side panels thereof, 55 a refractory lining coated on the interior of said sections, a single slab of refractory material at each side and at the bottom of the pot and adhered to said lining, a spout comprising a cylindrical tube in one of the second-mentioned corners bonded to the adjacent slabs, said pot being 60 adapted to be rotated on the trunnions in one direction for pouring molten metal from the pot through the spout and in the opposite direction for pouring directly from the other of said second-mentioned corners, said side sections being 65 readily separable upon disconnecting said bolts and keys and moving said side sections transversely of the pot, thereby breaking up said spout, each side section being coincidentally movable vertically relative to the other and 70 75

adapted to be broken away therefrom, the slabs covering substantially the full areas of the side sections and serving to promote separation of the refractory in large segments from the side sections during said movements of said side sections.

HAROLD WALLIS.
